Filed Sept. 5, 1972, Ser. No. 286,254

Term of patent 14 years

Int. Cl. D21—01

U.S. Cl. D34—3

FIG. 1

FIG. 2

FIG. 1 is a perspective view of a hexagonal billiard-type table showing my new design; and

FIG. 2 is another perspective view thereof.

The characteristic feature of my design resides in the combination of a massive hexagonal billiard table set on three turned spindle legs, each mounted under a pocket area.

I claim:

The ornamental design for a hexagonal billiard-type table, as shown and described.
